UNITED STATES PATENT OFFICE.

SAMUEL A. SUYDAM, OF NEW YORK, N. Y.

SIPHON FOR ICE-BOXES AND REFRIGERATORS.

SPECIFICATION forming part of Letters Patent No. 322,992, dated July 28, 1885.

Application filed May 21, 1885. (No model.)

To all whom it may concern

Be it known that I, SAMUEL A. SUYDAM, a citizen of the United States, residing at 550 Hudson street, in the city, county, and State 5 of New York, have invented a new and useful Siphon for Ice-Boxes and Refrigerators, of which the following is a specification.

My invention relates to improvements in detachable siphons; and the object of my improvement is to provide a siphon that shall cause the sediment and dirt to settle without choking either the siphon or the pipes, and that shall be easily removable to clean it out, as occasion may require, and to enable the 15 pipes to be cleaned out. I attain these objects by the construction illustrated in the accompanying drawings, in which—

Figure 1 is a view of an ice-box with my improved siphon in place. Fig. 2 is a sectional view of the siphon removed from the ice-box and the pipes, and Fig. 3 is a modified form of the siphon.

Similar letters refer to similar parts throughout the several views.

25 A is a pipe passing from the ice-chamber B to the interior of the ice-box, and to which the siphon is attached, and C is a pipe leading from the siphon to the pan D below; and it is obvious that when the siphon is removed 30 both A and C may be more readily cleaned than would be the case if there were one continuous pipe passing from the ice-chamber to the bottom of the ice-box, the siphon being placed under the bottom of the box, as is 35 commonly the case.

The siphon consists of the legs E and F, with the cross-piece G between them.

The opening between E and G is not equal to the full cross-sectional area of G, as is com-

monly the case, but is at the lower end only, 40 being shown at e. Similarly, the opening between F is not equal to the full area of either F or G, because F projects on one side unto G, as shown at f. Furthermore, the leg E passes down below its junction with G, leaving 45 a certain length of pipe in which the sediment and dust may accumulate and be subsequently extracted by removing the cork H. Whatever sediment may, however, find its way into the branch G will be induced to settle by the 50 projection f, which will arrest the flow of water through the lower half of G, and this sediment will have a tendency to slide down the branch G and into the leg E.

In the modification shown in Fig. 3 the 55 opening between E and G is at the top of their point of junction, and it is obvious that the dirt and sediment could accumulate up to the dotted line J before choking the siphon.

It is obvious that the projection f may be 60 of any desired height, and that there may be one or more of the openings e between leg E and branch G.

Having fully described my invention, what I desire to claim and secure by Letters Patent 65 is—

In a siphon for ice-boxes, the leg E, projecting below the branch G, so as to form a chamber for the reception of dirt and sediment, in combination with the opening e and the projection f, the siphon being detachable, to enable it to be cleaned and to facilitate the 70 cleaning of the pipes in the ice-box, substantially as set forth.

SAMUEL A. SUYDAM.
